UNITED STATES PATENT OFFICE

WILLIAM G. ABBOTT, JR., OF WILTON, NEW HAMPSHIRE

APPARATUS FOR USE IN SPOOL-DYEING YARNS

Application filed March 12, 1926. Serial No. 94,165.

This invention pertains to the spool dyeing of textile yarns, roving, etc., and more particularly to apparatus so devised as to permit determination of the progress of the operation from time to time without necessitating the drainage of the kettle or vat or prolonged interruption of the process.

By reason of the many and varying factors involved in textile dyeing, particularly the 10 non-uniform character of the fibre employed as respects its capacity to absorb dye stuffs and the varying characteristics of the dyes employed, it is substantially necessary at intervals during the dyeing process to inspect 15 the material in order to determine the progress of the operation. While such inspection is comparatively easy in open kettle or vat dyeing when the yarn is in the form of hanks which may readily be lifted from the dye 20 liquor from time to time, it is quite another matter to determine the progress of the operation when dyeing yarn by the pressure process upon large and heavy dresser spools or warp beams.

25 In the practice of the spool or pressure dyeing process the kettles usually employed are provided with one or more special apertures or holes at convenient points, such holes being provided with covers which must first be removed when a sample is to be taken and then a certain quantity of the yarn or thread 30 is pulled off from the spool for inspection. This mode of sampling is unsatisfactory since the small piece of thread pulled off from the spool may not be a fair sample of the 35 mass on the spool while it frequently involves breakage or snarling of a large amount of yarn and at best is slow and difficult to perform. Another method is to place a loose piece of the material in the dye kettle, removing 40 it from time to time for inspection, but here again the sample may not be representative of the mass upon the spool since the mode of application of the dye is quite different in 45 the two cases.

In accordance with the present invention I provide ready means for removing an entire spool from the dye kettle or vat for sampling purposes, this being accomplished without 50 draining the kettle or stopping the operation

for more than a few minutes. By thus exposing the entire spool to view the operator is able to obtain a much more accurate knowledge of the progress of the operation than by examination of small and often unrepresentative samples.

When a one spool vat is employed the one spool which carries the yarn is used for sampling but when the vat contains a large number of spools certain selected ones of these 60 spools are arranged for sampling in accordance with my present invention.

In the accompanying drawings I have illustrated a preferred embodiment of the invention as applied to a multiple spool kettle, it 65 being understood that substantially the same arrangement may be used in a one spool kettle.

In the drawings:

Fig. 1 is a vertical section, with certain 70 parts broken away, illustrating my invention as applied to a dye vat of usual type, the section being substantially on the line 1—1 of Fig. 2;

Fig. 2 is a plan view of the device shown in Fig. 1 on a smaller scale and with certain 75 parts omitted;

Fig. 3 is a fragmentary side elevation, partly in section, showing the lower part of 80 the dye kettle, the spools being omitted; and

Fig. 4 is a side elevation to larger scale showing one of the spool supporting sleeves.

Referring to the drawings for a more detailed description of the invention, the numeral 1 designates a dye kettle or vat, here shown as cylindrical, provided with a bottom 2. The vat is also furnished with a false bottom 3 spaced from the bottom 2 to provide a plenum chamber 4.

An outlet conduit 5 opens at a point 6 (Fig. 2) substantially at the center of the vat and above the false bottom 3, such conduit extending down through the plenum chamber and through the bottom of the vat to the inlet 90 of a circulating pump 7. The outlet of the pump is connected to a delivery conduit 8 which opens at 9 (Fig. 2) into the plenum chamber 4. Preferably the inlet conduit 5 is of a diameter substantially greater than 95 100

the diameter of the outlet conduit 8 so as to avoid cavitation at the inlet of the pump.

The false bottom 3 of the vat is furnished with a plurality of openings corresponding 5 to the number of spools which the vat is intended to receive and each of these openings is furnished with a bushing or sleeve 10 (Fig. 4) which extends downwardly into the plenum chamber 4 where it is provided with 10 openings or slots 11 to admit fluid from the plenum chamber to the interior of the bushing.

Each of the bushings 10 is furnished at 15 its open end with an annular flange 12 resting upon the upper surface of the false bottom 3 and which is adapted to support the lower head 13 of a spool. As here shown, the spool is provided with a hollow barrel 14 and with an upper head 15, and preferably 20 the upper end of the sleeve 10 is furnished with a beveled or conical surface 16 which assists in centering the spool when it is placed in the vat.

The spools employed are furnished with 25 perforated barrels and the yarn mass Y is wound thereon, preferably with an open wind, to facilitate the passage of the dye liquor from the interior of the spool outwardly.

As ordinarily arranged, each spool is set 30 down into the vat so that its upper head is below the low water level of the dye-liquor and each spool is furnished with a member 17 engaging its upper head. This member 17 forms a cover for the upper end of the spool 35 barrel and has a central opening for the passage of a rod 19 which is anchored at its lower end by means of a suitable nut or other device and which is screw-threaded at its upper end to receive a nut 18 by which clamping pressure 40 may be applied to the cover member 17 to hold the spool in operative position. The rod 19 passes up through the corresponding sleeve 10 and through the barrel of the spool, and when the spool is clamped in position the 45 cover 17 prevents escape of the dye liquor through the upper end of the spool so that it is constrained to pass outwardly through the perforations in the barrel and out through the yarn mass upon the barrel.

In order to insure uniform dyeing of the 50 yarn upon the spool it is considered necessary to maintain the cool or low level of the dye liquor at a point somewhat above the upper end of the spool, but when the liquor is heated 55 to the boiling point by the introduction of steam, the level soon rises considerably higher as indicated at W by reason of the condensation of the steam. Since the usual clamping means comprising the cover 17 and the nut 18 60 is below the low level, it is impossible to remove a spool for sampling without first partially draining the vat.

In accordance with the present invention, one of the spools is furnished with

a special annular cover 20 (Fig. 1) provided with a tubular upwardly extending stem 21. The stem 21 may or may not be integral with the cover proper as desired.

The lower end of the stem 21 is closed by 70 means of a plug 22 having a central aperture adapted to permit passage of a rod 19^a which is anchored at its lower end in any suitable manner, as for example, by means of the nut 23. The rod 19^a is longer than the rods 19 75 usually employed and extends up through the stem 21 to a point above the upper end of the latter. The upper end of the stem is disposed well above the level W of the boiling liquid and its upper end is closed by means of a cap 24 fitting snugly therein. This cap is furnished with a central aperture for the passage of the upper end of the rod 19^a the latter being screw-threaded for the reception of a clamping nut 24^a.

When this special sampling spool has been set in place in the vat, the cover 20 with its sleeve 21 is slipped down over the rod 19^a until it bears against the upper end of the spool. The nut 24^a is then applied to the upper end of the rod 19^a and screwed down against the cap 24 to apply the desired clamping pressure to the spool. When it is desired to remove the spool for sampling purposes, the nut 24^a may readily be removed from the rod 19^a since it is disposed above the level of the liquid in the kettle. Preferably though not necessarily I stop the circulating pump for a few minutes while the spool is being put in place or is being removed. The cap 20 is then 90 lifted and the spool is thus released for removal.

In accordance with the present invention, I provide means for lifting the spool from the dye liquor consisting of a tongs device comprising a cross bar 25 having arms 26 and 27 pivotally secured to its opposite ends. These arms 26 and 27 are furnished at their lower ends with jaws 28 adapted to engage the flange of the upper head of the spool. The 100 tongs is also provided with crossed link members 29 and 30 attached to the opposite ends of the cross bar 25 and these links are connected by a chain 31 adapted to engage a hook 32 forming part of a hoisting tackle 110 33 of any suitable type. Preferably this hoisting tackle is mounted upon a trolley 34 adapted to travel along a rail 35 carried by the arm 36 of a crane or other suitable supporting means.

After the spool has been unclamped as above described, the tongs device is lowered into the vat until the jaws 28 engage the upper head of the spool. The tongs is then lifted, 125 thus raising the spool from the dye liquor to permit inspection of the yarn mass thereon.

While certain specific arrangements of parts have herein been shown, it is to be understood that various modifications and sub- 130

stitutions of equivalents may be made without departing from the spirit of the invention.

I claim:

1. Apparatus for use in spool dyeing yarns comprising an open-topped vat, means for supporting a plurality of spools vertically in the vat, and clamping means for holding the spools in position, the clamping means for one of said spools being disposed above the 10 clamping means for the other spools whereby to permit said clamping means to be exposed above the surface of dye liquor covering the clamping means for the other spools.

2. Apparatus of the class described comprising an open-topped vat, means for supporting a plurality of spools vertically in the vat, said spools being substantially alike and of the kind having perforated hollow barrels and spaced relatively-fixed heads, means for 20 closing the upper end of the barrel of each spool, and releasable clamping means for each spool, the clamping means for one of the spools being disposed in a plane above that of the clamping means for the other 25 spools whereby to permit it to be exposed above the surface of dye liquor covering the clamping means for the other spools.

3. Apparatus for use in the spool dyeing of textile materials upon a spool of the kind having a perforated tubular barrel of fixed 30 length provided with a head at each end, said apparatus comprising an open-topped vat substantially deeper than the length of the spool, means for supporting a plurality of 35 spools of substantially the same size in substantially vertical position in the lower part of the vat, each spool when so supported having its upper head below the top of the vat, and releasable clamping means for holding 40 each spool in operative position upon its support, the clamping means for one of the spools being disposed above the clamping means for the other spools whereby to permit it to be exposed above the surface of dye 45 liquor covering the clamping means for the other spools.

4. Apparatus for use in the spool dyeing of textile materials upon a spool of the kind having a perforated tubular barrel of fixed 50 length provided with a head at each end, said apparatus comprising a vat substantially deeper than the length of the spool, and means for holding a plurality of such 55 spools, all of substantially the same size in upright position in the vat, said means comprising a rod for each spool, each rod being anchored at its lower end to the vat and adapted to extend up through the barrel of 60 the spool and to project above the top of the spool, and releasable clamping means engaging the projecting upper end of each rod, one of said rods being longer than the others, whereby the clamping means associated therewith may be exposed above the surface

of dye liquor covering the clamping means for the other spools.

5. Apparatus for use in the spool dyeing of textile materials upon a spool of the kind having a tubular perforated barrel of fixed length provided with a head at each end, said apparatus comprising an open-topped vat substantially deeper than the length of the spool, means for holding a plurality of such 70 spools all of substantially the same length in upright position in the vat, said holding means comprising a cover for each spool adapted to engage the upper end of the spool and to close the axial opening in the spool barrel, and releasable clamping means 75 engageable with each cover, one of said covers comprising a sleeve with the upper end of which the corresponding clamping means is associated, said sleeve projecting upwardly to a plane above that of the other covers whereby its associated clamping means may be always exposed above the level of dye liquor covering the clamping means for the other spools.

6. Apparatus for use in the spool dyeing of textile materials upon a spool of the kind having a tubular perforated barrel of fixed length provided with a head at each end, said apparatus comprising an open-topped vat substantially deeper than the length of the spool, means for holding a plurality of such 90 spools all of substantially the same length in upright position in the vat, each with its upper end below the top of the vat, said holding means comprising an annular 95 cover for the upper end of each spool, a rod extending up through each cover, each rod being anchored at its lower end to the vat and being screw-threaded at its upper end, one of said covers comprising a tubular stem 100 extending upwardly to a point above the other covers and having a cap at its upper end provided with a central aperture, the corresponding rod being of greater length than the other rods and extending up through 105 said stem and the aperture in the cap, and a clamping nut engaging the threaded end of each rod for releasably retaining the corresponding cover and spool in operative position, the nut for the longer rod being at such 110 an elevation as to expose it above the level of dye liquor covering the clamping nuts for the other spools.

7. Apparatus for use in the spool dyeing of textile materials upon a spool of the kind having a tubular perforated barrel of fixed length provided with a head at each end, said apparatus comprising an open-topped vat substantially deeper than the length of the spool, the vat having a plurality of fluid inlet orifices at its lower part, an annular spool support surrounding each orifice, each such support being provided with a conical surface for centering the spool with the bore in the spool concentric with the orifice, and 125 130

means for holding a plurality of spools, each of substantially the same length in operative position in the vat with the lower end of each spool seated on one of said annular supports, 5 said holding means comprising a retaining element engageable with the upper end of the spool, a releasable clamping device engageable with each retaining element, the clamping device for one of said spools being disposed at a point above the clamping devices for the other spools so that it may be exposed above the level of dye liquor covering the other clamping devices, means for forcing fluid through said orifices into the 10 interior of the several spools, and means for removing that spool having the elevated clamping device from the kettle, after release of its clamping device, without disturbing the clamping devices for the other spools 15 and without substantially changing the level of the dye liquor.

Signed by me at Wilton, New Hampshire,
this 9th day of March, 1926.
